UNITED STATES PATENT OFFICE.

CHARLES J. AHRENFELDT, OF NEW YORK, N. Y.

DESIGN FOR A COVERED DISH.

SPECIFICATION forming part of Design No. 32,423, dated April 3, 1900.

Application filed January 8, 1900. Serial No. 790. Term of patent 7 years.

To all whom it may concern:

Be it known that I, CHARLES J. AHRENFELDT, a citizen of the United States, residing in the city of New York, county of New York, 5 and State of New York, have invented and produced a new and original Design for a Covered Dish, of which the following is a specification, reference being had to the accompanying drawings, forming a part hereof, and like 10 letters referring to like parts in each figure of the same.

In the said drawings, Figure 1 is a side view of a covered dish, showing my design. Fig. 2 is a top view of the same.

15 The body A of the dish is provided with four pairs of vertical grooves or indentations A', running from the curved base A² to the upper edge and connected by a transverse ridge A³. The cover B is also provided with 20 like grooves B', extending on radial lines from the center and diverging to meet the grooves A' at the edge thereof. They are connected by transverse grooves B². Between the grooves of each pair and near the top of 25 the dish is a harp-shaped ornament, with leaves A⁴ projecting therefrom, while below it is a bell-shaped floral ornament with pendent tendrils A⁵. The same two ornaments B⁴ B⁵ reversed, are displayed between the radial

grooves B' of the cover. Between the grooves 30 at the base of the dish is the scroll-like ornament A⁶ and between the two pairs of grooves on either side of the dish the ornament A⁷, which consists of a floral figure with scrolls at either side.

35 The ornament A⁸ is located near the upper edge of the dish and on the outer side of each groove. Like ornaments B⁸ are similarly situated near the outer edge of the cover.

The curved handle of the cover C at the top 40 and center thereof is provided with volute scroll ornaments C', as is also the cover at the part C² where the handle is joined to it.

45 The curved handles D of the dish at either end are provided with scroll ornaments D', similar to the ornaments C' of the cover-handle, and a like ornament D² proceeds from the point where each end of the handle is joined to the dish along the side thereof.

50 What I claim is—

The design for a covered dish substantially as herein shown and described.

Signed at New York city, New York, this 28th day of December, 1899.

CHARLES J. AHRENFELDT.
